CLAIM

The ornamental design for packaging, as shown and described.

DESCRIPTION

FIG. 1 is a top, front perspective view of a packaging showing the claimed design, consisting of a lid, outer portion and inner portion;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top, front perspective view of the packaging of FIG. 1 in an open configuration with the inner portion of the packaging shown partially removed from the packaging;

FIG. 9 is a front view of the inner portion of the packaging of FIG. 8 shown separately to show aspects of the design that may not be apparent in the other views;

FIG. 10 is a rear view thereof;

FIG. 11 is a left side view thereof;

FIG. 12 is a right side view thereof;

FIG. 13 is a top view thereof;

FIG. 14 is a bottom view thereof; and,

FIG. 15 is a top front perspective view thereof.

1 Claim, 7 Drawing Sheets
